OPTICAL MEANS FOR DETECTING
COUNTERFEIT MONEY

Edwin W. Horan, Norwalk, Conn.

Application April 8, 1938, Serial No. 201,016

3 Claims. (Cl. 88—39)

This invention relates to improvements in devices for use by cashiers or other people handling money, which will assist them in the ready detection of counterfeit money.

An object of my invention is to provide a device used in the detection of counterfeit money, which may be secured to a cash register, and comprises means for holding a bill and an adjustably supported magnifying glass whereby a person may magnify the printing upon the face of the bill, to assist them in determining whether the bill in particular is a counterfeit one, or one which is good.

Another object of my invention is to provide a device used in the detection of counterfeit money, which will include a support having spring fingers for supporting a bill in question, together with means for supporting a magnifying glass adjustable toward the bill holding means whereby printing on the bill may be examined in detail to determine its authenticity, and means whereby magnifying lenses of different power may be readily inserted in the device.

A further object of the invention is to provide an improved device used in the detection of counterfeit money, which will be highly efficient in use, and quite inexpensive to manufacture.

Other objects will appear as the description proceeds.

30 In the accompanying drawing which forms a part of my application,

Figure 1 is a side elevation of a cash register with my improved device applied thereon;

Figure 2 is a longitudinal sectional view through my improved detection device;

Figure 3 is a sectional view taken on the line 3—3 of Figure 2;

Figure 4 is a sectional view taken on the line 4—4 of Figure 2;

Figure 5 is a sectional view taken on the line 5—5 of Figure 2, and

Figure 6 is a sectional view taken on the line 6—6 of Figure 4.

Like characters of reference are used throughout the following specification and the accompanying drawing to designate corresponding parts.

In carrying out my invention, I provide a detection device for detecting counterfeit money, which consists of a bill holding frame 2 adapted to be secured in any desired position upon a cash register 1, and a magnifying lens holding frame adjustable with respect thereto.

The bill holding frame 2 is substantially rectangular in shape, and is provided with a pair of

spaced spring bill holding fingers 3 secured to the lower surface of said bill holding frame 2 and extending upwardly in contact therewith. Suitable bolts will be positioned through the bill holding frame 1, and will extend through the surface or wall of the said cash register 1, to firmly secure the device in position on the said cash register. The bill holding frame 2 is provided with a laterally extending base portion 4 formed with the upwardly and inwardly extending flanges 5 and 6, the adjacent edges thereof forming a guideway 7, and cooperating limiting shoulders 8 and 9.

An magnifying lens holder 10 extends substantially parallel with the bill holder frame 2, and is rounded at its upper end, and is provided with the inwardly extending lens holding flange 11 extending about the rounded portion of the lens holder and down the opposite sides thereof. The lens holder 10 is also provided with a laterally extending base portion 12 which is adapted to be slidably received within the flanged portion of the base 4 of the bill holding frame 2, and is provided with an upturned centrally disposed guide and locking finger 13 which is adapted to slide within the guideway 7 in the bill holding frame 2 to prevent the complete withdrawal of the lens holder portion of the device from the bill holding frame. A magnifying lens 14 will be positioned within the lens holding flange on the lens holder 10, and an arcuate flanged member 15 is adapted to slide within the side flanges on the lens holder until it is positioned about the lower edge of the lens 14. The flanged member is provided with locking tongues 16 and 17 which are adapted to extend through suitable slots 18 and 19 formed in the flange 11 at the opposite sides of the lens 14, and will be bent downwardly against the outer surface of the said lens holding flange, thereby locking the magnifying lens 14 in fixed position within the lens holder. It will be understood that the arcuate flanged member may be removed when it is desired to replace the magnifying lens with one of a weaker or stronger power.

From the foregoing description, it will be apparent that when there is an uncertainty as to the authenticity of a bill, the bill will be placed under the spring fingers 3 and the magnifying lens will be moved forward and backward until it is in the proper focus to magnify the characteristics of the printing upon the bill, thereby enabling one familiar with the characteristic markings or printing upon good bills, to deter-

mine whether the bill in question is good or is counterfeit.

It will be further understood that while I have described and shown one form of detecting device for detecting the authenticity of bills, I do not intend to limit myself to the specific construction as described and shown, as many minor changes in detail of construction may be resorted to without departure from the spirit of the invention.

10 Having thus described my invention what I claim as new and desire to secure by Letters Patent of the United States is:

1. Optical means for detecting counterfeit money, including an apertured lens holder having a substantially semi-circular holding flange extending partly around the aperture and merging into substantially parallel portions, said flange providing a channel for the reception of a portion of the margin of a lens, a lens bridging the opening and having a portion of its margin extended into the channel, an arcuate flange member seated at its ends in the channel and lapsing a portion of the margin of the lens, cooperating means at the ends of said member and in 25 the flange on the holder for holding the arcuate member in engagement with the lens, a frame for supporting a bill and for engagement with and attachment to a supporting structure, a spring finger for binding the supported bill against the 30 frame to hold it across the focal axis of the lens, and an adjustable slidable connection between the frame and the lens holder.

2. The combination with means for engaging and supporting a bill and for attachment to a support, of magnifying means adjustably connected to said bill supporting means for movement toward and from the same, said means including an apertured lens holder, a lens bridging the aperture in the holder, a flange carried by the holder and lapsing a portion of the margin of the lens, said flange being extended along parallel lines away from the lens, an arcuate member insertable at its ends between the holder and flange into lapsing engagement with a portion of the lens, means for detachably connecting the ends of the arcuate member to the flange. 5

3. The combination with means for engaging and supporting a bill and for attachment to a support, of magnifying means adjustably connected to said bill supporting means for movement toward and from the same, said means including an apertured lens holder, a lens bridging the aperture in the holder, a flange carried by the holder and lapsing a portion of the margin of the lens, said flange being extended along parallel lines away from the lens, an arcuate member insertable at its ends between the holder and flange into lapsing engagement with a portion of the lens, and tongues projecting from the ends of the axis of the member, there being slots in the flange in which the tongues are seated, said tongues being in lapsing engagement with the 20 25 30 slotted flange.

EDWIN W. HORAN.
